UNITED STATES PATENT OFFICE.

OLIVER P. FRITCHLE, OF DENVER, COLORADO.

BATTERY.

1,415,541.

Specification of Letters Patent. Patented May 9, 1922.

Application filed April 12, 1920. Serial No. 373,220.

To all whom it may concern:

Be it known that I, OLIVER P. FRITCHLE, a citizen of the United States, residing at Denver, in the county of Denver and State 5 of Colorado have invented certain new and useful Improvements in Batteries, of which the following is a specification.

This invention relates to storage batteries and more particularly to mechanical 10 tails of construction thereof.

It is the general purpose of the invention to provide a battery unit of rugged mechanical construction.

A particular object is to provide means 15 for easily assembling the different elements in fixed relation as a single mechanical unit.

In order to more fully explain the nature 20 of the invention and its characteristic aspects I refer to the accompanying drawings in which—

Fig. 1 is a sectional view through a battery;

Fig. 2 is a fragmentary view of an inside 25 plate of one sign; and

Fig. 3 is a fragmentary view of an inside plate of opposite sign.

The casing 1, which is preferably a glass jar, has a recessed collar 2 defining an overhanging wall 3. The cover 4, preferably of 30 porcelain, has an upwardly beveled edge 5 adapted to be loosely received in the recess of the collar 2. The space intermediate the overhanging wall 3 of the jar and edge 5 is filled with a suitable cement which in 35 hardened condition forms a secure seal 18 and at the same time interlocks the jar and the cover against relative movement.

As is usual, the plates of one sign are all 40 connected to strap 6 while the plates of opposite sign are connected to strap 7, which, in turn, form part of posts 8 and 9 respectively.

In order to quickly and effectively lock 45 the posts to the cover, I provide the posts with recesses 10 and the cover with recesses 11.

When the plates are in proper assembled 50 relation, the posts 8 and 9 are passed through the post holes in the cover plate so that the recesses 10 are accessible from above the plate and split washers 13 are inserted in the recesses. Then the cover is raised to its normal position relatively to the posts, as indicated in Fig. 1 and filler 55 block 12 is inserted between the plate straps 6 and 7 and the cover to lock the latter and

the unit battery element against relative movement.

Since the straps 7 and 8 are disposed entirely on one side of the vertical center line 60 of the plates, the plates have a tendency to sag down on one side. To prevent such sagging and fanning apart of the plates I provide on the bottom edge of the inside negative plates lugs 14 located slightly on 65 one side of the vertical center line thereof, on the positive plates lugs 15 disposed on the other side of the center line and on the outside negative plates lugs 16 in which are formed apertures 17 intersected by the 70 center line and pass a key 18 of insulating material through the space defined by the lugs 14 and 15 and through the apertures 17. This simple and cheap arrangement has the advantage that the parts may be 75 easily assembled and disassembled and held in a definite fixed position.

I claim:

1. In a battery, a casing having at its upper end a recessed collar defining overhanging interior walls and a cover plate 80 having upwardly beveled edges adapted to be seated in the recess of the collar.

2. In a battery, a casing having at its upper end a recessed collar defining overhanging interior walls, a cover plate having upwardly beveled edges and a filler intermediate the said walls and the edges. 85

3. In a battery, the combination of a cover plate having an orifice, a post extending 90 through the orifice, means adapted to be attached to the post above the cover plate to define a shoulder against the upper surface of the cover plate and means adapted to be inserted in the space between the plate 95 straps and the lower surface of the cover plate to lock the latter and the post against relative movement.

4. In a battery, the combination of a cover plate having an orifice, a post extending 100 through the orifice and having a peripheral recess, means adapted to be inserted in the said recess to define a shoulder against the upper surface of the cover plate and means adapted to be inserted in the space between 105 the plate straps and the lower surface of the cover plate to lock the latter and the post against relative movement.

5. In a battery, the combination of a cover plate having an orifice and a recess in its 110 upper surface around the orifice, a post extending through the orifice, means adapted

to be attached to the post to fill the recess in the cover plate and define a shoulder against the cover plate and a filler block adapted to be inserted in the space between the plate 5 straps and lower surface of the cover plate.

6. In a battery, the combination of a cover plate having an orifice and a recess in its upper surface around the orifice, a post extending through the orifice and having a 10 peripheral recess, a split washer adapted to be inserted in the said peripheral recess and to take up the space defined by the recess in the cover plate and a filler block adapted to be inserted in the space between the plate 15 straps and the lower surface of the cover plate.

7. In a battery, the combination with the alternate positive and negative plates and straps and posts located on opposite sides 20 of the vertical center line of the plates, of lugs disposed on the lower edge of the outside plates, said lugs having each an aperture substantially in the central vertical

plane of the plates, of lugs on alternate inside plates, disposed on one side of the central vertical plane, and lugs on the remaining alternate plates disposed on the other side of the central vertical plane. 25

8. In a battery, the combination with the alternate positive and negative plates and 30 straps and posts located on opposite sides of the vertical center line of the plates, of lugs disposed on the lower edge of the outside plates, said lugs having each an aperture substantially in the central vertical 35 plane of the plates, of lugs on alternate inside plates disposed on one side of the central vertical plane, lugs on the remaining alternate plates disposed on the other side of the central vertical plane and a key member extending through the space intermediate the oppositely disposed lugs and received in the apertures of the lugs on the outside plates. 40

In testimony whereof, I affix my signature. 45
OLIVER P. FRITCHLE.
